(57) **CLAIM**

The ornamental design for a three-wheeled sedan, as shown and described.

DESCRIPTION

FIG. 1 is a front perspective view of a three-wheeled sedan showing the design.

FIG. 2 is a left side elevational view of the three-wheeled sedan showing the design.

FIG. 3 is a right side elevational view of the three-wheeled sedan showing the design.

FIG. 4 is a front elevational view of the three-wheeled sedan showing the design.

FIG. 5 is a rear elevational view of the three-wheeled sedan showing the design.

FIG. 6 is a top plan view of the three-wheeled sedan showing the design; and,

FIG. 7 is a bottom plan view of the three-wheeled sedan showing the design.

The wheels shown in broken lines are for illustrative purposes only and form no part of the claimed design.
